CLAIM

The ornamental design for a handle for a display, as shown and described.

DESCRIPTION

FIG. 1 is a front perspective view of a handle for a display showing our new design.

FIG. 2 is a back perspective view of the handle for a display of FIG. 1.

FIG. 3 is a front view of the handle for a display of FIG. 1.
FIG. 4 is a back view of the handle for a display of FIG. 1.
FIG. 5 is a left side view of the handle for a display of FIG. 1.

FIG. 6 is a right side view of the handle for a display of FIG. 1.

FIG. 7 is a top view of the handle for a display of FIG. 1; and,

FIG. 8 is a bottom view of the handle for a display of FIG. 1.

The broken lines in FIGS. 1–8 are included for the purpose of illustrating environmental structure and form no part of the claimed design.
